(57) **CLAIM**

The ornamental design for a combined rotary hand pump and drum connector, as shown and described.

DESCRIPTION

FIG. 1 is a perspective view of the combined rotary hand pump and drum connector.

FIG. 2 is a front elevation view of the combined rotary hand pump and drum connector.

FIG. 3 is a first side elevation view of the combined rotary hand pump and drum connector.

FIG. 4 is a second side elevation view of the combined rotary hand pump and drum connector.

FIG. 5 is a rear elevation view of the combined rotary hand pump and drum connector.

FIG. 6 is a bottom view of the combined rotary hand pump and drum connector; and,

FIG. 7 is a top plan view of the combined rotary hand pump and drum connector.
